(57) **CLAIM**

The ornamental design for a LED pet collar, as shown and described.

DESCRIPTION

FIG. 1 is a first perspective view of a LED pet collar showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the LED pet collar in which the design is embodied that form no part of the claimed design.
